UNITED STATES PATENT OFFICE.

SERAFIM PEREIRA REZENDEZ, OF NEW BEDFORD, MASSACHUSETTS.

INCINERATOR.

1,113,049.

Specification of Letters Patent.

Patented Oct. 6, 1914.

Application filed February 26, 1914. Serial No. 821,184.

To all whom it may concern:

Be it known that I, SERAFIM PEREIRA REZENDEZ, a subject of Portugal, and resident of New Bedford, Bristol county, and State of Massachusetts, have invented certain new and useful Improvements in Incinerators, of which the following is a specification.

This invention relates to an incinerator for burning or destroying the contents of sputum cups and the like.

The principal object of the invention is to provide a simple and inexpensive incinerator which may be set in the flue of a furnace or other conduit carrying hot gases and flame.

The above and other objects and novel features of the invention will be apparent from the following description, taken in connection with the drawings in which:

Figure 1 is a vertical sectional view of a furnace and the flue thereof, with an incinerator constructed according to my invention set in the flue line, parts being shown in side elevation. Fig. 2 is a horizontal cross section of the incinerator taken along the line 2—2 of Fig. 1; and Fig. 3 is a vertical cross section of the incinerator taken along the line 3—3 of Fig. 1.

Referring to the drawings, 10 designates the fire-box of a furnace of any ordinary or preferred construction, the walls 11 thereof supporting a boiler 12 through the tubes of which the flame and hot gases from the fire-box escape to the vertical flue 13 at the front end of the boiler. Extending rearwardly from near the upper end of the vertical flue 13 there is a short horizontal flue section 14 in which a damper 15 is pivoted. The damper is arranged to shut off the heat supplied to the incinerator.

The horizontal section 14 of the flue is connected to the rectangular metal box 16 at the opening 17 therein. The box 16 may rest on the upper side of the boiler 12 or be supported above the latter by means of brackets 16' as indicated. The box 16 may be made of boiler iron or other suitable material and reinforced with angle irons at the corners and has a door 18 hinged at one side and closing the opening 19' through which the matter and articles to be incinerated are introduced into the interior of the incinerator. A latch 18' or other suitable device may be provided for locking the door 18.

Extending along parallel sides of the box 16 and secured to the walls 19 and 20 are

angle irons 21 and 22, which support the ends of the grate bars 23 of the incinerator, a slight distance above the bottom of the box 16 to provide an unobstructed passage beneath the grate. At each end of the supports 21 and 22 and extending above the same to the top of the box 16, there is a series of rods 24 at one end and 25 at the other, which rods extend across the box 16. The rods 24 and 25, together with the grate bars 23, form an openwork inclosure accessible to the hot gases and flame and within which the articles to be incinerated are placed. The rods 24 and 25 may be spaced apart any suitable distance sufficient to exclude foreign matter from the said inclosure. The flame and hot gases entering horizontally through the bars 24 and upwardly through the grate 23 are broken up and are brought into intimate contact with the said matter. It will be seen that the support formed by the grate bars 23 is located slightly below the center-line of the flue pipes 14, 27, so that the entering gases will pass above and below said support. The top of the box as well as the deflector 28 will direct the heat down onto the support and the matter thereon and part of the heat will pass through the bars 24, 25 over the support directly to the outlet 26.

The gases, etc., discharge from the incinerator through the opening 26 which is located in line with the opening 17, and has the flue pipe 27 connected thereto, the latter leading to the stack (not shown). In order to deflect the gases into cups or similar vessels, I have provided a curved deflector plate 28 which is pivoted at 29 at the upper ends of the forward cross bars 24. To raise and lower the deflector plate 28 and change the angle at which it hangs, I provide a bar 30 which is pivoted to the upper side thereof, passes through an opening in the top wall of the box 16, and has notches 31 or other suitable means co-operating with the opening for maintaining it in a given position.

A steam pipe 32 leads into and along the bottom of the box 16 beneath the grate and has branches 33 which extend across the bottom of the box 16. The steam pipes are perforated along their upper edges so as to permit the escape of steam therefrom. In order to lead hot gases directly to the incinerator without having them pass through the flues of the boiler 12, I provide a pipe 34 which is connected to the rear end of the

furnace chamber and leads to an opening in the side of the box 16 above the grate bars 23, having a valve 34' by means of which it may be regulated or shut off.

- 5 When it is desired to introduce a crate of sputum cups or other articles to be incinerated, the damper 15 is closed while the door 18 is opened. When the cups are set in place on the support formed by the grate bars 23, the door is closed and the damper opened, allowing heated gases and flame from the flue to enter the incinerator and circulate through the same. When the incineration is completed, the damper is closed 10 and the door may be opened and the cups removed. To thoroughly clean the box after the incinerating operation, the door 18 is again closed and while the damper remains closed, live steam is turned on at the valve 15 32'. When the box has been thoroughly cleansed, the damper may be opened until it is desired to use the incinerator again. The incinerator will not obstruct the passage 20 of dust and the like through the flue into the smoke stack as it will be observed there is an obstructed passageway which leads between the openings 17 and 26 at the opposite ends of the pipe and underneath the grate bars 23.

From the foregoing description, it will be 30 seen that I have provided an incinerator which has decided advantages over other devices of this type and over the old method of burning or disposing of the sputum. Heretofore, it has required a very heavy fire 35 and has been a very disagreeable and unhealthy task for the fireman to properly dispose of the sputum, whereas by using the present arrangement the incineration is carried on in a sealed box and without any 40 danger to the fireman or other person charged with the work.

It will be apparent that various changes may be made in the construction without departing from the spirit of the invention, and 45 therefore I do not wish to be limited to the exact details as shown and described.

Having thus described my invention what I claim is:

1. The combination with the flue of a furnace of an incinerator comprising an inclosing casing having openings at its ends adapted to be connected to the flue, a grate above the bottom of said casing and between the openings in the ends thereof, a series of 50 rods at each end of the grate and rising to the top of the incinerator, a steam admission

pipe below the grate, a door in the side walls of said casing and above the grate, and adjustable means for deflecting onto the material to be incinerated the hot gases entering from said flue.

2. In an incinerator, the combination of a box having a heat inlet and an outlet and an opening to admit matter to be incinerated, a support for said matter located above the bottom of the box and between said inlet and outlet, means above the inlet for directing heat onto the support and the matter thereon which is to be incinerated, a steam pipe leading into said box, and means for shutting off the supply of heat entering said box through said inlet.

3. In an incinerator, the combination of a box having a heat inlet and an outlet, a pipe leading to the inlet and a pipe leading from said outlet, a support above the bottom of the box and below a line connecting the centers of the inlet and outlet, means above the inlet for directing heat onto the matter to be incinerated and means for shutting off the heat entering said box through said inlet.

4. The combination with a furnace having a flue, of an incinerator set in said flue and comprising a box having an inlet and an outlet in its opposite end walls and a normally closed opening in its side wall, a supporting grate above the bottom of the box and below a line joining the centers of the inlet and outlet, an upwardly extending grating at each end of the supporting grate, means for directing heat onto the supporting grate, a steam pipe leading into said box, and means for shutting off the supply of heat entering said box through said inlet.

5. The combination with a box having an inlet and an outlet, of a grating extending horizontally across the box above the bottom and vertically at a distance from the ends of the box to the top of the latter, said grating forming an inclosure with the sides and top of the box, said inclosure having an entrance for the introduction of matter to be incinerated, and a device in the inclosure for deflecting on to said matter the hot gases entering the box through said inlet.

In testimony whereof I affix my signature in presence of two witnesses.
